(57) **CLAIM**

The ornamental design for a triceps pull down rope as shown and described.

DESCRIPTION

FIG. 1 is a front perspective view of the triceps pull down.

FIG. 2 is a front view of the triceps pull down rope;

FIG. 3 a rear view of the triceps pull down rope;

FIG. 4 is a left side view of the triceps pull down rope;

FIG. 5 is a right side view of the triceps pull down rope;

FIG. 6 is a top view of the triceps pull down rope; and,

FIG. 7 is a bottom view of the triceps pull down rope.

The broken lines show portions of the triceps pull down rope that form no part of the claimed design.

1 Claim, 4 Drawing Sheets
